US0D1077863S

(12) **United States Design Patent** (10) **Patent No.:** **US D1,077,863 S**
(45) **Date of Patent:** **** Jun. 3, 2025**

(54) **MANIFOLD COVER**

(71) Applicant: **Accessible Technologies, Inc.**, Lenexa, KS (US)

(72) Inventor: **Cliff Hall**, Lee's Summit, MO (US)

(73) Assignee: **Accessible Technologies, Inc.**, Lenexa, KS (US)

(**) Term: **15 Years**

(21) Appl. No.: **29/887,977**

(22) Filed: **Mar. 27, 2023**

(51) **LOC (15) Cl.** **15-01**

(52) **U.S. Cl.**

USPC **D15/5**

(57) **CLAIM**

The ornamental design for a manifold cover, as shown and described.

DESCRIPTION

FIG. 1 is a front perspective view of a manifold cover, showing my new design;

FIG. 2 is a second front perspective view thereof;

FIG. 3 is a third front perspective view thereof;

FIG. 4 is a rear perspective view thereof;

FIG. 5 is a second rear perspective view thereof;

FIG. 6 is a front view thereof;

FIG. 7 is a rear view thereof;

FIG. 8 is a right side view thereof;

FIG. 9 is a left side view thereof;

FIG. 10 is a top view thereof;

FIG. 11 is a bottom view thereof; and,

FIG. 12 is an environmental view thereof.

The broken lines in the drawings illustrate portions of the manifold cover that form no part of the claimed design.

1 Claim, 10 Drawing Sheets
